UNITED STATES PATENT OFFICE.

ADELMA J. THERREAULT, OF SEYMOUR, CONNECTICUT.

BUCKLE.

1,367,215.

Specification of Letters Patent.

Patented Feb. 1, 1921.

Application filed May 24, 1920. Serial No. 383,735.

To all whom it may concern.

Be it known that I, ADELMA J. THERREAULT, a citizen of the United States, residing at 37 Church St., Seymour, county of 5 New Haven, State of Connecticut, have invented an Improvement in Buckles, of which the following is a specification.

This invention relates more especially to the type of buckles used in attaching a web 10 to a safety pin of the hump type, as for use in stocking supporters in which the web is adjustably attached to the pin which in turn attaches the supporter as a whole to a corset, waist or other article of apparel, and 15 the invention has for its object to provide a buckle of this type in which the frame of the buckle shall be adapted to slide over the hump of the safety pin, and which shall provide for the attachment 20 of the web to the buckle without stitching and for adjustment of the buckle on the web in the usual manner, the buckle as a whole being simple in construction and inexpensive to produce, the amount of metal 25 required being reduced to the minimum, as there is little waste in the form of scrap, and the number of mechanical operations being likewise reduced to the minimum, the buckle frame being first blanked out and then 30 formed ready for assembling by a second operation.

With these and other objects in view I have devised the novel buckle which I will now describe, referring to the accompanying 35 drawing forming a part of this specification and using reference characters to indicate the several parts.

Figure 1 is an elevation on an enlarged scale illustrating the use of my novel buckle 40 in connection with an ordinary stocking supporter;

Fig. 2 a section on the line 2—2 in Fig. 1 looking in the direction of the arrows;

Fig. 3 a perspective view of a safety pin 45 of the hump type;

Fig. 4 a perspective view of my novel buckle detached;

Fig. 5 an elevation of the blank from 50 which the buckle frame is formed;

Fig. 6 a modified form of buckle; and

Fig. 7 is a sectional view of the buckle of Fig. 6, illustrating the use of the modified form of buckle with a stocking supporter.

Referring to Figs. 1 to 5 inclusive, 10 denotes a safety pin of the type referred to,

which comprises the usual pin, coil, guard and the hump which is specifically indicated by 11. The buckle frame is blanked out complete as shown in Fig. 5 and comprises a plate 12, ears 13 which are bent at 60 right angles to the plate and are provided with holes 14 to receive the trunnions 15 of the lever 16. The lever may be of the friction type or may be provided with teeth 17 which are adapted to be forced into the web 65 to lock the buckle to the web when the lever is turned to operative position. In addition to the ears the plate is provided with straps 18 which are adapted to be curved outward from the plate, in the opposite direction 70 from the ears, and then bent parallel with the plate to form an elongated socket 19 which loosely receives the hump of the safety pin, the buckle frame as a whole sliding over the hump of the pin. 75

In assembling the parts of the supporter, the buckle frame is first slid up on the hump to about the position shown in the drawing. An end 20 of the web is next positioned between the arms of the hump and inserted 80 downwardly into the socket. The web is then drawn around the outer portions of straps 18, as denoted at 21, is then passed forwardly between the lower edge of the plate and the base of the hump, as denoted 85 at 22, is then drawn around the front face of the plate beneath lever 16, as denoted at 23, is then passed rearwardly over the top edge of the plate, as denoted at 24, is then drawn across the portion of the web designated 21, as denoted at 25, is again passed forwardly between the lower edge of the plate and the base of the hump, as denoted at 26, is formed into a loop 27 for the clasp 90 of the supporter, is again passed between the lever and the front face of the plate, as denoted at 28, is then drawn around the portions of the web designated 24 and 25, as denoted at 29, and is again passed forwardly 95 between the lower edge of the plate and the base of the hump, as denoted at 30.

It will be noticed that three thicknesses of web rest beneath straps 18. Protection of the body of the wearer from the metallic parts of the buckle is thus insured. It will 105 also be noticed that the loop may be adjusted in length in a simple and convenient manner.

When the stocking supporter is put to use, downward pulling on the loop, it will be ap- 110

parent, will cause the web to be firmly gripped and held between the lower edge of the plate and the base of the hump for the reason that the buckle frame is arranged to 5 freely slide over the hump.

Referring to Figs. 6 and 7, 31 denotes a plate of modified form which is provided with a struck up bar 32, and with straps 33, which are arranged on the opposite side 10 of the plate from the struck up bar, to provide a socket 34. The manner of assembling the parts of the web is as before, as will be apparent from Fig. 7, the struck up bar acting as a substitute for ears 13 15 and lever 16.

What I desire to claim is:

1. A buckle of the character described, comprising a plate from the front face of which extends web holding means and from the 20 rear face of which extends straps shaped into the form of an elongated socket whereby the buckle as a whole can be slid over the hump of a safety pin and positioned to receive a web.
2. A buckle of the character described, comprising a plate provided with forwardly extending web holding means and carrying on its rear face an elongated socket which 25

is adapted to loosely receive the hump of a safety pin.

3. A buckle of the character described, comprising a plate provided with forwardly extending web holding means, and with rearwardly extending straps shaped into the form of an elongated socket said web holding means being integrally attached to the plate and said socket extending across the rear face thereof and adapted to loosely receive the hump of a safety pin.

4. A buckle of the character described, comprising a plate provided with forwardly extending web holding means, said web holding means being integrally connected to said plate, and with rearwardly extending straps which are integrally attached to the ends of the plate and formed into an elongated socket which is arranged to slide over the hump of a safety pin and to receive an end of a web, the buckle as a whole being so constructed that the web can 50 be drawn therearound to be securely and adjustably held by the buckle and suspended from the safety pin.

In testimony whereof I affix my signature.

ADELMA J. THERREAU.
